DESIGN FOR AN ICE CRUSHER

William P. Koch, Chicago, Ill., assignor to Chicago Die Casting Manufacturing Company, a corporation of Illinois

Application January 13, 1940, Serial No. 89,451

Term of patent 3½ years

To all whom it may concern:

Be it known that I, William P. Koch, a citizen of the United States, residing in Chicago, county of Cook, State of Illinois, have invented a new, original, and ornamental Design for Ice Crushers, of which the following is a specification, reference being had to the accompanying drawing, forming part thereof.

Figure 1 of the drawing is a side elevational view, slightly in perspective, of an ice crusher embodying my design; and Figure 2 is a front elevational view of said ice crusher.

I claim:

The ornamental design for an ice crusher, as shown.

WILLIAM P. KOCH.
